APPARATUS FOR REMOVING LEAVES FROM GUTTERS

Herbert Copelin Bugbird, Summit, N. J.

Application January 13, 1953, Serial No. 331,083

4 Claims. (Cl. 15—172)

This invention relates to apparatus for removing leaves from the gutters of house roofs.

Unless leaves are removed, they mat down into waterproof masses that clog gutters and downspouts or leaders. Usually the cleaning out of house gutters is a time-consuming and difficult job. When a ladder is used, it must be moved to many different locations, and the person doing the job has to climb up and down the ladder at each new location.

It is an object of the invention to provide improved apparatus by which house gutters can be cleaned of leaves by a man standing on the ground. The apparatus is simple and inexpensive in construction; and it can be used conveniently and effectively without previous experience.

Other objects, features and advantages of the invention will appear or be pointed out as the description proceeds.

In the drawing, forming a part hereof, in which like reference characters indicate corresponding parts in all the views,

Figure 1 is a view showing the way in which the invention is used for cleaning roof gutters at different heights from the ground;

Figure 2 is a greatly enlarged view of the cleaning apparatus shown in Figure 1;

Figure 3 is a fragmentary view showing the way in which the cleaning apparatus of Figure 2 fits into a gutter, when in use;

Figure 4 is an end view of the apparatus shown in Figure 3;

Figure 5 is a fragmentary view showing a different cleaning device which may be used in place of the brush, shown in Figures 2-4;

Figure 6 is a diagrammatic view showing the projection, on a vertical plane, of the arc of swing of the cleaning tool when in operation; and

Figure 7 is a diagrammatic plan view showing the projection, on a horizontal plane, of the path of swing of the cleaning tool.

Figure 1 shows a house 10, with a roof gutter 11 at a relatively high level, and another roof gutter 12 at a much lower level on a lean-to extension of the house. The cleaning apparatus includes a support 15 comprising a handle 17 and an extension 18 which are held and manipulated by an operator 20, standing on the ground at a short distance out from the wall of the house.

The extension 18 is preferably of composite construction, consisting of separate lengths of tubing 18' which can be connected together to increase the length of the extension so as to reach higher gutters, when necessary. In the construction shown in Figure 2, the handle 17 screws into the lower length of tube 18', and the separate lengths of tubing are connected together by screw threads, but other kinds of connections can be used.

At the upper end of the extension 18, there is a bracket rigidly connected to the extension. This bracket includes

2

a head 21 and tool holder 23, the latter being connected to the head by a pivot connection 24, and this holder 23 carries a tool which serves as a cleaning device for the gutter. Figures 2-4 show a cleaning device consisting of a brush 25, but with leaves and other material which has not become matted down on the bottom of the gutter, a wire loop 26 (Figure 5) serves as an adequate tool or cleaning device for removing the leaves and similar loose material. Referring again to Figure 2, the holder 23 and brush 25 swing as a unit about the pivot connection 24. The direction of this swinging movement is in a plane co-incident with or parallel to a plane through the longitudinal axis of the support 15. The holder 23 and brush 25 are held in any desired adjusted position by a stud 28 and wing nut 29. The stud 28 extends from the holder 23 through a slot 30 in the head 21. The nut 29, on the opposite side of the head from the holder 23, clamps the holder 23 against the head 21 so that the holder is held against relative movement by friction against the head.

It is a feature of this invention that the holder 23, and the support comprising the head 21, extension 18 and handle 17 are a substantially rigid unit when the holder is secured in any adjusted position. The support has a longitudinal axis which extends at a substantial angle to both the horizontal and vertical when the invention is in use. It is also a feature of the invention that the support and in the construction illustrated, the head 21 of the bracket has a bottom surface which extends across the outer edge 32 (Figure 3) of the gutter. The apparatus is operated by moving the brush 25, or other tool, along the length of the gutter to accumulate leaves, or other material, in front of the brush. The operator then rotates the support 18 about its longitudinal axis to cause the brush to raise the leaves, or other material, up and over the forward edge with a sort of spooning motion.

The holder 23 is adjusted, about its pivot connection 24, so that the brush 25, or other tool, extends downwardly and inwardly with respect to the gutter. The reason for the adjustability of the invention is to enable the same apparatus to be used with gutters of different size and shape, though for a particular house owner, it is sufficient to make one initial and permanent adjustment of the angle of the brush for the particular style and size of roof gutter on his house.

Some resilience is permissible in the tool that serves as a cleaning device, but only a limited amount of resilience, because the tool must swing through an arc about the longitudinal axis of the support in order to obtain the spooning action of the preferred embodiment of the invention.

While the apparatus is being moved along the gutter to accumulate a pile of leaves ahead of the brush, the support may rest on the outer edge 32 of the gutter, or may be spaced some distance above the outer or top front edge of the gutter, depending upon the way in which the operator holds the support and whether the brush is in a vertical position or dragging at an angle to the bottom of the gutter. When the operator turns the handle about its longitudinal axis, to swing the brush for spooning leaves over the side of the gutter, the sloping portion of the support above the gutter edge 32 will contact with the gutter edge and serve as a bearing on which the entire apparatus rocks while the leaves are being raised and spooned over the edge of the gutter. Thus the surface of the apparatus that contacts with the top front edge of the gutter provides a bearing on which the apparatus rocks to give the cleaning device or brush 25 an angular movement about an axis of rotation extending in substantially the same direction as the longitudinal axis of the handle projection.

This swinging movement of the brush, or other tool, is best understood by reference to Figures 6 and 7.

Figure 6 is a diagram looking at the gutter 12 from the front. As the extension 18 is rotated about its longitudinal axis, the holder 23 swings the lower end of the brush, or the tool, through an arc 35, which is elliptical in the vertical projection shown in Figure 6. This diagram brings out the way in which the brush or other tool swings upwardly on a long arc with respect to the vertical.

Figure 7 is a diagram looking down on the gutter 12. As the extension 18 swings about its longitudinal axis, the motion of the lower end of the cleaning tool is along the arc 35' which is elliptical in its horizontal projection. This view brings out the way in which the tool moves toward the front of the gutter 12 and over the side of the gutter as the tool moves upwardly.

The preferred embodiment of the invention has been illustrated and described, but changes and modifications can be made without departing from the invention as defined in the claims.

What is claimed is:

1. Cleaning apparatus for removing leaves and other obstructions from a roof gutter which has a top front edge extending substantially parallel to an adjacent wall of a house, said apparatus including a handle with a long projection for reaching up to the gutter from the ground, the handle projection reaching upwardly across the top front edge of the gutter and having a longitudinal axis diverging downwardly away from said wall at a substantial angle to the vertical when the cleaning apparatus is in working position, a head connected to the upper end of the handle projection, a cleaning device attached to the head, a bearing on the cleaning apparatus near the upper end of the handle projection and in position to be brought into contact with the top front edge of the gutter, the bearing being unobstructed for free rocking movement on said top front edge about an axis of rotation extending in substantially the same direction as the longitudinal axis of the projection of the handle and in response to oscillation of the handle projection about its longitudinal axis, the cleaning device extending from the head downwardly into the gutter and as far as the bottom of the gutter when the handle is in one angular position about the longitudinal axis of the handle projection, and said cleaning device having a front-to-back dimension, in the direction of the extent of the gutter, less than the up-and-down length of the cleaning device and connections securing the handle, projection, head and cleaning device together into a unitary structure whereby oscillation of the handle and the

projection about the longitudinal axis of said handle projection produces corresponding angular movement of the cleaning device about said axis of rotation extending in substantially the same direction as the longitudinal axis of the handle projection whereby the cleaning device moves with a single compound movement having a forward-and-aft component that lifts the leaves from the bottom of the gutter, and a transverse component that lifts the cleaning device and the leaves over the top front edge of the gutter.

10 2. The cleaning apparatus for roof gutters described in claim 1 and in which the vertical extent of the cleaning device below the level of said bearing is somewhat greater than the depth of the gutter in which the apparatus is intended to be used so that the bearing is above the edge of the gutter when the apparatus is in working position and the cleaning device is disposed in a plane substantially normal to the wall of the house whereby the bearing on which the apparatus rocks contacts the front surface of the gutter only after the handle projection has been rotated through an angle about its longitudinal axis.

15 3. The cleaning apparatus for roof gutters described in claim 1 and in which there are adjustable fastening means connecting the cleaning device to the head, the fastening means being movable to change the angle of the cleaning device with respect to the handle projection in a plane normal to the wall of the house.

4. The cleaning apparatus for roof gutters described in claim 1 and in which the bearing that contacts with the 20 top front edge of the gutter extends away from the longitudinal axis of the handle projection in a direction having its principal component in a horizontal plane when the apparatus is in working position with respect to a gutter to be cleaned.
